KNITTING NEEDLE

William Henry Robert Dunn, North Hollywood,
Calif., assignor of forty-nine per cent to
Ferdinand A. Datig, Los Angeles County, Calif.

Application June 15, 1938, Serial No. 213,794

7 Claims. (Cl. 66—117)

This invention relates to a flexible knitting needle of the type used for continuous knitting in a circular form.

In the knitting of skirts, sleeves and other articles, the general practice is to continuously knit in a circle until the entire garment is finished. This requires either a set of three or more needles of the ordinary rigid type or the use of a needle composed of two rigid tips connected with a flexible cable or wire. This invention relates to a needle with tips and flexible cable.

In knitting with the flexible cable type of needle the user is continually twisting and turning the tips, causing a twist in the cable. As a result the cable breaks after a period of time. Failure of the cable means a dropping of stitches and either the destruction of the article being knitted or a great loss of time and energy in recovering the dropped stitches.

It is an object of this invention to provide a knitting needle of the flexible cable type which will not break from twisting.

In knitting it is often desirable to alter the size of the stitches. Prior to this invention it was necessary to change the article being worked on from one set of needles to a set of needles of different size. This invention makes possible the change of the size of the stitch by merely changing the size of the tips attached to the flexible cable.

When it is desired to lay aside a piece of work using ordinary needles, it is necessary to shove the material well away from the tips to prevent stitches from coming off the ends. In circular knitting there is practically no chance to do this as the knitted article bridges the gaps between the points and tends to pull the stitches off of the needle. This invention, by means of guards replacing tips, prevents a loss of stitches from the needle.

In the drawing:

Fig. 1 is a plan view of a knitting needle made in accordance with this invention.

Fig. 2 is a cross section of part A of Fig. 1.

Fig. 3 is a cross section of the tips of the needle.

Fig. 4 is a plan view of various tips.

Fig. 5 is a cross section of the guard used to replace the tips.

Fig. 6 is a fragmental sectional view of a modified form of knitting needle embodying my invention.

1 and 2 are flexible cables or wires forming the base of the knitting needle. A swivel A joins the two ends of the cables. This swivel is formed of a tip 3 having therein a bore 20 for insert-

ing and welding or soldering cable 1. The cylindrical boss 4 attached to tip 3 has an indentation 5. The body member 6 has a cylindrical cavity 7 into which is placed the boss 4. The body member 6 has a hole through it at 8 to provide for a retaining pin 9 which fits into the indentation 5 and prevents a withdrawal of the boss 4. The pin 9 is held in place by welding or soldering on the outside of the body member 6. It is readily apparent that body member 6 can now be rotated in relation to tip 3 but cannot be removed therefrom. Body member 6 has a threaded end 10 to engage complementary threads on tip 11. Tip 11 is soldered or welded to cable 2 as was tip 3 to cable 1. The tips 3 and 11 of the swivel are tapered to make a uniform slope from the flexible cables over which the stitches may be readily moved. This taper must fit exactly the flexible cable and the outside of the body member 6. The joints between the cable and the swivel and between the various parts of the swivel must be smooth and without any projection so as to permit the free passage of stitches across the swivel. It is also necessary that the swivel member never be larger than the smallest size tips 12 placed on the ends of the cables 1 and 2.

Tips 12 are composed of Celluloid or a plastic and have a cavity 13 for receiving an internally threaded nut 14. The nut 14 engages a bolt 15 which has a section 16 tapering into the ends of the cables 1 and 2. The bolt 15 has a cavity 17 for inserting and welding therein the cables 1 and 2. The tips 12 can be removed by merely unscrewing the nut 14 from the bolt 15 and interchanging it with any size of tips as displayed in Fig. 4.

When it is desired to lay aside the work, the tips 12 may be unscrewed and replaced by the guard 18 which is composed of a nut having thereon a flange 19 to retain stitches on the needle and internally threaded to receive the bolt 15.

A feature of this invention is that the tips 12 may be made in various contrasting colors so that different colored tips can be used to contrast with the yarn so that even in poor light the stitches will be more clearly apparent.

When it is desired to make articles of varying sizes such as a skirt, cuffs or neck-band, the size of the needle may be made smaller or larger by removing the tip 11, adding a length, or inserting in its place a tip 12. If the article is larger than ordinary, an extra cable 1 with swivel attached can be attached to the nut 14 and tip 12 placed on the other end.

In the modified form of my invention illustrated in Fig. 6, the cable 1^a is connected with the tip 3^a in any suitable manner, preferably as illustrated and described in connection with the first modification. In this form of my invention swivel means are interposed between the point 12^a and the tip 3^a. This positioning of the swivel at this point permits the maintaining of a swivel within the knitting needle no matter where or to what section or sections of the cable the knitting needle is connected. In this form of construction the swivel may be formed by positioning within a cavity 20^a formed in a plug 14^a in the end of the point 12^a, a spring expansion ring 21^a. This ring 21^a is cut at 22^a to permit the same to expand to receive the ball 23^a within the cavity 20^a. The ball 23^a is secured to the end of the reduced diameter rod 24^a, which rod 24^a may be formed integral with the tip 3^a. The ring 21^a is fitted into the enlarged ring recess 25^a to permit the same to expand therein when the ball 23^a is moved into the cavity 20^a.

Another distinct feature of my invention lies in the fact that the points or tips 12 or 12^a are made of different colored material. Thus when one is knitting, the color of the tip or point 12 or 12^a used contrasts with the yarn color when, for example, white yarn is used, a red or blue tip 12 or 12^a is used. When a dark yarn is used, 30 a white or yellow tip or point is substituted.

Having fully described my invention, it is to be understood that I do not wish to be limited to the details herein set forth, but my invention is of the full scope of the appended claims.

I claim:

1. In a knitting needle, the combination of flexible cables connected by a swivel means, said flexible cables having rigid tips at the ends away from said swivel means.

2. In a knitting needle, the combination of 40 flexible cables connected by a swivel means, said

flexible cables having removable rigid tips at the ends away from said swivel means.

3. In a knitting needle, the combination of flexible cables connected by a swivel means, said flexible cables having removable rigid tips at the 5 ends opposite said swivel means, means for disconnecting said cables at the swivel means to either shorten or lengthen said needle by inserting an extra flexible cable or placing a rigid tip in place of one cable. 10

4. In a knitting needle, the combination of flexible cables connected by a swivel means, said swivel means having tapered tips, a body member, said body member being connected to one of said tapered tips by a swivel joint and threadably engaging the other said tip, said flexible cables having rigid tips at the ends away from 15 said swivel means.

5. In a knitting needle, the combination of flexible cables connected by a swivel means, said 20 swivel means having tapered tips, a body member, said body member being connected to one of said tapered tips by a swivel joint and threadably engaging the other said tip, said flexible cables having removable rigid tips at the ends 25 away from said swivel means.

6. In a flexible knitting needle, the combination of flexible cables joined by a swivel and having removable rigid tips at the extremities.

7. In a knitting needle, the combination of 30 flexible cables connected by a swivel means, said swivel means having tapered tips, a body member, said body member being connected to one of said tapered tips by a swivel joint and threadably engaging the other said tip, said tapered 35 tips having bores thereon for inserting and welding said flexible cables, said flexible cables having rigid tips at the ends away from said swivel means.

WILLIAM HENRY ROBERT DUNN. 40
